UNITED STATES PATENT OFFICE.

CHARLES HAMMER, OF HOLLIS COURT BOULEVARD, NEW YORK.

SPACED OR SECTIONED CONTINUOUS-THREAD CONTAINER AND CAP THEREFOR.

Application filed July 7, 1923. Serial No. 650,115.

To all whom it may concern:

Be it known that I, CHARLES HAMMER, a citizen of the United States, residing at Hollis Court Boulevard, in the county of 5 Queens and State of New York, have invented certain new and useful Improvements in Spaced or Sectioned Continuous-Thread Container and Cap Therefor, of which the following is a specification.

10 This invention relates to containers, particularly to that class of containers primarily adapted for use with metal caps or closures, such as glass containers, the improvement having to do particularly with the threaded 15 portions of such containers, the object of the invention being to provide an improved thread on a glass container particularly adapted for use with what is known as a "continuous thread" cap, whereby certain 20 disadvantages heretofore present in the use of continuous thread caps are eliminated, the quick application and ready removal of the cap facilitated, and the effective drawing down and complete sealing of the container 25 insured.

Glass containers as manufactured today are divided into two main classes, one having the neck or top of the container provided with continuous threads complementary to 30 similarly formed threads on the cap, and the other having the top or neck of the container provided with what is known as "divided threads" for use with similarly formed threads or lug projections on the cap. The 35 continuous thread glass container has its thread starting at a predetermined point from the mouth or top of the neck and running without interruption entirely around the neck, terminating at or adjacent to the 40 shoulder of the container and comprises one complete thread but usually several overlapping threads according to the number of threads per inch that the container is provided with. A divided thread container has 45 each thread starting at the same point from the mouth or top of the container and terminating at the same point at or adjacent to the shoulder.

For many reasons it has been found that a 50 divided thread container and cap is superior to a continuously threaded one. Some of

these reasons are that a divided thread jar and cap enables the cap to be more uniformly drawn down and consequently a better sealing of the jar is effected. The cap 55 can be more quickly applied and more easily removed, and the sticking and binding usually present when a continuous thread is used sometimes requiring the application of mechanical means, as a cold chisel or a vise in 60 order to remove the cap, is eliminated. On the other hand, there are some advantages in a continuous thread cap which make this form of cap desirable for use with certain products, among which is that such a cap can 65 be more uniformly made and probably more economically produced, but so far as I am aware, it has not been heretofore possible to use a continuously threaded cap on anything 70 but a continuously threaded jar or container. 75

It is a fact that glass containers are not uniform, and this can be easily demonstrated by taking several glass containers of the same size and construction, and placing them mouth downward upon a level surface, and it 75 will be found that the top edge of the container more or less varies so that the jar more or less wobbles. In other words, the upper edge of the container is not entirely uniform, one part projecting to a greater extent than another. Consequently on the application of the cap it will fit more tightly at one part than at another, so that the container is not efficiently and effectively sealed, unless all parts of the cap are uniformly drawn down. 80 This uniform drawing down is better obtained by a divided thread cap than by a continuous thread cap because the continuous threads of the cap so stiffen the flange of the cap that there is no opportunity for the cap 85 to yield and conform to the inequalities of the sealing surface or edge of the container, and consequently it does not fit as tightly or as well as where there is a uniform drawing down. It is for this reason that it has been 90 the practice to a large extent to provide the cap and container with divided threads, since these divided threads will insure a more even drawing down of the cap. A divided thread 95 cap on the other hand has the disadvantage because of the sharp inclination of the thread to prematurely come loose or ride off the 100

threads of the container, and thus loosen the cap, and unseal the container. This disadvantage is not present in a continuous thread cap, since the long gradual continuous thread effectively holds the cap on the bottle against any such premature unsealing or opening, but a continuous thread cap requires that it be entered on the jar at just one point, and requires several turns to turn it on and turn it off. For these reasons, and others, it has been largely superseded by the divided thread cap, which however as just stated, has the disadvantage of not as effectively holding on a container as a continuous thread, although its advantages have proven so much greater in other respects than a continuous thread that it has been largely adopted in place of such continuous thread.

The object of the present improvement therefore is to provide a threaded container, which can be used with a continuously threaded cap and which will combine the advantages of both the divided thread and the continuous thread, while eliminating the disadvantages of each, thus providing a very much improved container, and thus will permit the application of a continuous thread cap much more quickly and easily and eliminate the binding and sticking thereof.

In the drawings accompanying and forming a part of this specification, Fig. 1 is a top view of this improved container; Fig. 2 is a side view thereof with the cap in section; Fig. 3 is an enlarged view of the container and side view of the cap; Fig. 4 is a top and section view of the cap applied to the container; and Fig. 5 is a plan or lay-out view of the container illustrating the position of the threads end to end around the container.

Similar characters of reference indicate corresponding parts in the several views.

Before explaining in detail the present improvement and mode of operation thereof, it is desired to have it understood that the invention is not limited to the details of construction and arrangement of parts which are illustrated in the accompanying drawings, since the invention is capable of other embodiments, and that the phraseology which is employed is for the purpose of description and not of limitation.

The container 2, which may be of any suitable form, shape and material, is shown herein as a glass container in the form of a jar, and may be provided with the usual shoulder 3 and neck portion 4. This neck portion is provided with a plurality of lengthwise spaced threads 5, each equally spaced apart around the neck of the container, and each preferably of the same length, and were these threads connected and not endwise spaced they would form one continuous thread or spiral around the neck of the jar, and therefore by reason of

the spaces between the threads it will be observed that each thread or the working surface thereof is located at a different distance from the top of the jar compared with a companion thread or in other words that 70 thread, as D, which starts nearest to the top edge of the container and runs in an inclined direction toward the shoulder, has its under or working edge located nearer to the upper edge of the jar and further 75 from the shoulder, than the next following thread as C, which in turn is located nearer to the upper edge of the jar and further from the shoulder than the next following thread as B, and so on until the last thread 80 A is reached, which is located further from the top edge of the jar and nearer to the shoulder than any other companion projection. The under or working faces of each of these projections are inclined in the direction of their length from the top of the jar toward the shoulder when such is used, and all have the same inclination, thus each forms a thread or threadlike projection, and in practice the upper edges may be similarly 85 inclined.

By reason of this construction and the location of the threads around the neck of the jar, it will be seen that they are particularly adapted for the application of a continuously threaded cap.

In the present illustration four thread sections are shown, but the number thereof may vary according to the diameter of the container.

Among the advantages of the present improved construction is that it is unnecessary to form the glass thread all around the neck of the container, thus to this extent reducing the liability of fracture or imperfection in the thread, and also materially reducing the expense and labor of forming the metal molds, since it is unnecessary to cut the metal molds all the way around to form a continuous thread, it obviously requiring less labor and time to form a section of a thread in the metal mold or neck rings than to form the entire thread.

In addition as the thread on the container is arranged in sections or endwise spaced portions, it follows that if the jar is unevenly formed on its upper edge or mouth, these spaced sections will enable the cap to adapt itself to the unevenness of the sealing surface of the jar in the same way that a divided thread jar enables that form of cap to adapt itself to the sealing surface. In other words, the spaced or sectioned thread will draw the cap down uniformly to take up this unevenness in the sealing surface, and thus more effectively seal the jar than is possible with a continuously threaded jar and cap. That is to say, by forming the threads on the jar in the manner shown, the stiffness of the cap, due to

the formation of a continuous thread on the flange thereof, does not prevent an effective drawing down of the cap at all points, enabling the cap to yield as it were, at any 5 point of inequality on the upper edge of the jar due to the endwise spaced formation of the threads on the container.

Furthermore the formation of the threads in the manner disclosed enables a continuously threaded cap to go on easier and with less friction. In fact, by reason of the manner in which this improved thread is made, it has been found in practice that although a continuously threaded cap can- 10 not be entered on a continuously threaded receptacle, except at one point, to wit: the starting point of the thread at the upper end of the receptacle, yet in the present improvement by reason of the fact that the lower edge of the flange of the cap must slip over the threads in order to start the cap on the container, that a continuously threaded cap can be started on the container either at the point of the uppermost thread sec- 15 tion or at the next succeeding thread section, in which latter event the proper sealing of the cap is obtained by less rotation of the cap than has heretofore been possible with a continuously threaded cap and con- tainer. Thus in the present improvement, the cap can be started on at least two points on the receptacle, so that it is not necessary for the user to always start it at the same point, as has heretofore been neces- 20 sary with a continuously threaded receptacle. Due to this fact the cap will go on easier, and also will go on easier because there is less friction between the cap and the jar threads, since for each omitted thread section an equivalent amount of friction is eliminated. Thus this im- 25 proved formation of container thread assists in quick and easy placing of a continuously threaded cap on the jar, a quicker and a more effective sealing on the container than was heretofore possible with continuously threaded receptacles and caps. And furthermore by the improved formation of the threads in the manner shown and de- 30 scribed, there is no likelihood or danger of crossing the threads on the application of the cap, as is frequently the case with a continuously threaded receptacle and cap, ren- dering it at times almost impossible to re- 35 move the cap by hand, and at times impos- sible to remove it even by the application of mechanical means without the breakage of the glass container with the possibility of glass fragments getting into the contents and making it necessary to either throw away the contents or run the risk of serious injury to the user, aside from the danger of cutting the hands in an attempt to loosen the cap.

Notwithstanding my long experience of

many years in the cap making art, and consequent long familiarity with the glass making art, I am unaware of any container having a similarly formed thread to that herein shown and described, and since the 70 thread is neither a continuous thread nor a divided thread for the reasons hereinbefore stated, I have elected to call it a spaced or sectioned continuous thread, since it will cooperate with a continuously threaded cap, 75 but not with a divided thread cap of the usual form, in which the divided threads all start and terminate at the same points on the flange of the cap.

In Fig. 3 is illustrated one form of continuously threaded cap 6, which may be used with this improved container, and it comprises a top 7 having a depending shallow skirt or flange 8 provided with a reinforced or strengthened lower edge 9, as by 80 rolling, curling or beading the edge, and with a surface for facilitating the handling of the cap as well as the strengthening thereof, and in the present instance this surface is shown as a polygonal surface 10 of 85 decagon form, that is, it has ten flat sides, although this surface could be corrugated or otherwise formed if preferred. This construction, as well as the beaded or curled edge, strengthens both the cap and the flange of the cap, while the latter prevents the cutting of the hands and the rusting of the cap at this point. Between this polygonal surface and the strengthened edge 90 is located the continuous thread 11, which at the lower entering end 12, is narrow and shallow and gradually deepens and widens, as it progresses around the cap for a large portion of the flange of the cap, thus forming what may be considered in one sense as 95 a wedge of two dimensions, that is, a wedge in height as well as in depth. The end of this continuous thread of course deepens and grows shallow toward the top of the cap and may or may not overlap the for- 100 ward end of the same thread.

It is to be understood that by describing in detail herein any particular form, structure or arrangement, it is not intended to limit the invention beyond the terms of the 105 several claims or the requirements of the prior art.

Having thus explained the nature of my said invention and described a way of constructing and using the same, although 110 without attempting to set forth all of the forms in which it may be made, or all of the modes of its use, I claim:

1. A container having a lengthwise spaced or sectioned continuous thread, 115 whereby said sections would, if connected, form a spiral.
2. A container having a plurality of threads spaced lengthwise from each other, and each located at a different point on the 120

12. A sealed package comprising a container having a lengthwise spaced or sectioned thread, whereby said sections, if connected, would form a spiral and a shallow flanged metal cap comprising a top and a depending shallow flange or skirt having a polygonal portion, and a curled, rolled, or beaded edge, and therebetween a continuous thread. 70
13. A sealed package comprising a glass container having a lengthwise sectioned or spaced continuous thread, whereby said sections, if connected, would form a spiral a metal cap thereon having a shallow depending flange or skirt provided with a roughened surface reinforcing said cap and flange, a beaded, curled or rolled lower edge also reinforcing said flange and therebetween a wedge-shaped projection narrow and shallow at one end and merging into a wider and deeper portion. 75 80
14. A sealed package comprising a glass container having a lengthwise spaced or sectioned continuous thread, whereby said sections, if connected, would form a spiral a metal cap thereon comprising a top having a depending shallow flange provided with a polygonal portion, a strengthened lower edge, and therebetween a projection narrow and shallow at one end, merging into a wider and deeper portion. 90 95
15. A glass container having a series of endwise spaced threads or threadlike projections, each starting and terminating at a different point relatively to the top of the container from every other projection, whereby said projections, if connected, would form a spiral. 100
16. A glass container having a series of endwise spaced threads or threadlike projections, each starting and terminating at a different point relatively to the top of the container from every other projection, the starting end of one projection and the terminating end of another being lengthwise spaced in the same inclined plane, whereby said projections, if connected, would form a spiral. 105 110
17. As an article of manufacture, a container and a removable flanged cap therefor, one having endwise spaced elongated projections extending all around the article and having their holding edges inclined and disposed in different horizontal planes from the top to form and have the location of a continuouslike thread, whereby said projections, if connected, would form a spiral, and the other having a continuous threadlike projection for engagement with said spaced projections. 115 120
18. As an article of manufacture, a container and a removable flanged cap therefor, one having a series of substantially equally spaced elongated projections of substantially equal length extending all around 125 130
1. A container relatively to its companion threads, whereby said spaced threads would, if connected, form a spiral.
2. A container having a plurality of lengthwise spaced threads, the inclined lower edge of each being in the same inclined plane as companion threads, whereby, if connected, they would form a spiral. 5
3. A container having lengthwise spaced or sectioned threads located and positioned if connected to form a spiral to receive a continuously threaded cap. 10
4. A glass container having a plurality of lengthwise spaced or sectioned threads, the lower edge of each having the same inclination as companion threads, whereby, if connected, they would form a spiral. 15
5. A glass container having a plurality of lengthwise spaced or sectioned threads, the lower inclined edge of each prolonging the inclined lower edge of companion threads, whereby, if connected, they would form a spiral. 20
6. A glass container having a plurality of lengthwise spaced or sectioned threads, the lower inclined edge of each prolonging the inclined lower edge of companion threads, and each thread having its entire lower edge spaced differently from the top 25 of the container than the lower edge of all of its companion threads, whereby, if connected, they would form a spiral.
7. A glass container having a plurality of lengthwise spaced or sectioned threads, the lower inclined edge of each prolonging the inclined lower edge of companion threads, and each thread having its entire lower edge spaced differently from the top 30 of the container than the lower edge of all of its companion threads, whereby, if connected, they would form a spiral.
8. A sealed package comprising a container having a lengthwise spaced or sectioned continuous thread, whereby said sections, if connected, would form a spiral and a continuously threaded cap thereon. 35
9. A sealed package comprising a container having a lengthwise spaced or sectioned continuous thread, whereby said sections, if connected, would form a spiral and a continuously threaded cap thereon, said cap comprising a top and a depending shallow flange or skirt having therein a roughened surface. 40
10. A sealed package comprising a container having a lengthwise spaced or sectioned continuous thread, whereby said sections, if connected, would form a spiral and a continuously threaded cap thereon, said cap comprising a top and a depending shallow flange or skirt having therein a roughened surface, and a strengthened or reinforced lower edge with the continuous 45
